HOOD LATCH UNIT

Robert L. Townsend, Sherman Oaks, Calif., assignor to
A. C. Stearns Co.

Filed Oct. 30, 1969, Ser. No. 19,855

Term of patent 14 years

Int. Cl. D8—04

U.S. Cl. D8—265

FIG. 1 is a perspective view of a hood latch unit in accordance with the present invention therefor, taken from the bottom thereof;

FIG. 2 is a perspective view of the mounting bracket portion thereof;

FIG. 3 is a side elevational view of the present invention shown in latched position;

FIG. 4 is a front elevational view of the present invention shown in non-latched position; and

FIG. 5 is a top view of the present invention.

The vehicle hood portion shown in broken lines is included for illustrative purposes only.

I claim:

The ornamental design for a hood latch unit, substantially as shown and described.
